W. E. WINE,
CAR DOOR LOCK.
FILED JAN. 10, 1922.

8 William E. Wine,
By Parker Cook.
Attorney.

UNITED STATES PATENT OFFICE.

WILLIAM E. WINE, OF TOLEDO, OHIO.

CAR-DOOR LOCK.

Application filed January 10, 1922. Serial No. 528,246.

To all whom it may concern:

Be it known that I, WILLIAM E. WINE, a citizen of the United States of America, residing at Toledo, in the county of Lucas 5 and State of Ohio, have invented certain new and useful Improvements in Car-Door Locks, of which the following is a specification.

My invention relates to new and useful 10 improvements in car door locks and more especially to a lock to be used on gondola or hopper cars which types of cars are provided with drop bottom doors.

One of the principal objects of the present 15 invention is to provide a car door lock wherein the door may be elevated to a preliminary supported position and from which it may be forced up into its final locked position.

20 As is well known to those familiar with the art, the drop doors of a car often become warped or distorted and are not easily swung into their locked or set position. Furthermore, often a few loose pieces of 25 coal or dirt will wedge along the sides of the door or along the hinged edge making it necessary to exert great pressure on the door just before the same reaches its final or locked position.

30 One of the objects of the present invention, therefore, is to provide a locking device wherein the door may be raised to a preliminary supported position, and after which the device may be operated to quickly 35 force the door upwardly into its final and locked position.

Still another object of the invention is to 40 provide a lock comprising a hook pivoted to a short arm, which arm in turn is pivoted to the side of the car, the first mentioned 45 pivotal point being capable of being swung over to one side of the axis of the second pivotal point so that the hook will remain in its locked position until swung back manually.

Still another object of the present invention is to provide a locking device comprising 50 a hook that will first support the door in a preliminary position, after which the hook may be swung past a center so that the door will be raised to its final position and there held; and to provide supplemental means in the way of a dog to further hold the aforementioned lock in its set position 55 with the door.

Another object of the invention is to provide with a pivoted door-supporting hook, a door having an arm, preferably of an angular section, with a reinforcing hook seat secured thereto and which may have one 60 or more end walls to prevent creepage of the hook along the arm.

Still another object of the invention is to provide a car door lock which will be relatively light in weight, exceedingly strong, 65 and relatively cheap to manufacture and assemble.

With these and other objects in view, the invention consists in certain new and novel construction and combination of parts as 70 will be hereinafter more fully described and pointed out in the claims.

Referring now to the drawings showing a preferred embodiment of the invention—

Fig. 1 is a view in elevation showing a 75 fragmentary portion of a side of a car, a car door, the same being shown in its closed and locked position, and the locking device, this being slightly enlarged with relation to the door for the sake of clearness.

Fig. 2 is a sectional view taken on line 80 2—2 of Fig. 1.

Fig. 3 is a view similar to Fig. 1 in this instance, however, the lock being in its open 85 position and the door being shown as supported in a preliminary or temporary position.

Fig. 4 is a detail section view on line 4—4 of Fig. 1.

In the drawings, a fragmentary portion 90 1 of the side of a car is shown, beneath which is the bracket 2 which is secured to a center sill (not shown) and from which bracket is hinged the door 3, which is provided with the transversely extending angle iron 4 located near the outer edge of the door and on the end of which angle iron is riveted the bracket 5.

This bracket 5 may be provided with the lug or lip 6 to more firmly fit within the 100 jaw of the hook 7, shortly to be described.

The end bracket 5 constitutes an adapter casting for stiffening and reinforcing the angular section of the arm 4 and for forming a hook seat beneath one leg of the angle. 105 This casting 5 fits the inner contour of the angle iron and is also provided with end walls along either side of the hook seat to prevent slippage of the hook along the angle iron.

Referring now in particular to the improved lock or locking device, there is shown a hook 7 which comprises a body portion 8, the angular disposed upper shank 9, which is provided with the central opening 10, and, extending outwardly from the body portion 8 of the hook is the point or toe 9' which also extends slightly upwardly.

Passing through the opening 10 of the hook is seen the hollow sleeve 11 on which is swung and pivots the hook 7. This sleeve 11 is formed on one end of a short link or arm 12 while at the other end of the arm is a boss 13 through which is passed a short hollow bearing post 14, through which in turn is passed the rivet 15 so that the link or arm 12 with the hook 7 pivoted at its outer end may swing about the bearing post 14 as an axis. This bearing post 14 is formed integral with a strap 16 which extends rearwardly and is provided near its outer end with a second short bearing post 17 (see Fig. 4) through which is passed the rivet 18, this rivet and post pivotally securing an irregular shaped cam or dog 19.

The rivets 15 and 18 pass through the side of the car 1 and through a plate 20 located behind the plate 1 so that the locking device will be strongly held in position and will not be torn from the side of the car.

As will be seen in Fig. 1, when the door 3 is in its locked position, the hollow sleeve 11 which pivotally supports the hook 7 is to the left of the vertical plane of the lower pivotal point of the arm 12, or past dead center so that the hook will hold or support the load in this, the set position, as long as these parts remain in these respective positions. The inward movement of the arm 40 and hook is limited as the inner surface of the hook 7 when shifted as shown in Fig. 1 will bear against the outer surface of the boss 13. The dog 19 is then swung to the position shown in Fig. 1 thereby locking the hook in its set position, the toe of the hook jamming against the lug 6 of the bracket 5.

To release the locking means or hook, a bar or rod (not shown) will be inserted in the hollow sleeve 11 and the hook forced rearwardly, the dog 19, of course, having first been swung over and out of the way, the upper end 9 of the hook 7 swinging rearwardly until the upper pivotal point 10 thereof is beyond the vertical plane of the lower pivotal axis at which time the door and hook will drop to the position as shown in Fig. 3. The downward limit of movement of the hook 7 is fixed by the hollow sleeve 11 contacting with the upper surface or edge of the strap 16. The hook will then be hit or swung further rearwardly, that is about the sleeve 11 as an axis so that the jaw of the hook will be forced out of contact with the bracket 5 and the door will then fall to its open position.

To close and lock the door, the operation is simply reversed, the door being first lifted to a preliminary or temporary supported position as shown in Fig. 3, so that the jaw of the hook will pass within the bracket, 70 after which the bar will be inserted in the hollow sleeve and this upper pivotal point swung beyond the center of the lower pivotal point of the arm 12 which will hold the door in its set position, it having raised the door in its movement, after which the dog 19 will be jammed into place.

It will be seen that it is not absolutely necessary to have the bracket 5 at the end of the angle iron as the hook may contact directly with the angle iron, if desired, but the addition of the bracket adds but little expense and prevents any lateral movement of the door.

Although I have only shown one lock, it 85 will be understood that one is applied to each side of the car so that the door will be supported at its opposite sides. In most of the cars there are a number of doors and each door will be supported and locked by 90 two hooks. With a bracket as shown at each end of the angle iron, the door will be held against shifting or lateral movement as well as tightly in its horizontal position.

From the foregoing it will be seen that I 95 have provided a locking means that is relatively light in weight, cheap to manufacture, easily assembled and simple to operate.

Many slight changes may be made without in any way departing from the spirit and scope of the invention.

Having thus described my invention, what I claim and desire to secure by Letters Patent is:

1. In combination with a freight car, a hinged door, a hook for supporting the door in a slightly open position and said hook being eccentrically mounted with relation to said door so that when said hook is operated 100 to its final position, the door will be raised and locked in a closed position.

2. In combination with a car, a swinging door, a locking device secured at one side of said door and adapted to first support the door in a partly closed position, said locking device being eccentrically mounted so that the same may be operated to lift the door to its closed position and support and lock the same in this position.

3. In combination with a freight car, a swinging door, a locking device secured to the car body and adapted to engage said door and first support said door in a temporary position, said locking device being eccentrically mounted so that when swung said door will be raised to its final closed position and then locked, and auxiliary means for further locking said door in its closed position.

4. A locking device for swinging car doors 130

- comprising an arm, said arm adapted to be pivotally secured to the car body, a hook pivotally mounted on the upper end of said arm, said hook adapted to be swung to one side of the lower pivotal point of the arm to thereby retain the arm in a set position, and an auxiliary means for jamming against said hook to further provide against accidental disengagement of said hook.
10. 5. A car door locking device comprising a curved hook, an arm adapted to be pivoted to a car body, said hook pivoted to the outer end of said arm, the pivotal point of said hook being above that of the pivotal point of said arm, and said hook adapted to engage the door and to be swung beyond the dead center over the pivotal point of said arm to thereby retain the door in a supported and locked position.
15. 6. In combination with a freight car having drop doors, a locking device comprising an arm pivoted at its lower end to the side of the car body and above the car door, a curved hook mounted on the outer end of said arm, the pivotal point of the hook adapted to be swung to the right and left of the lower pivotal point of said arm, means on said door to be engaged with the said hook and outstanding means on said arm presenting a gripping surface whereby said arm may be moved about its pivot point as a center of rotation.
20. 7. In combination with a freight car having a drop door, said drop door provided with engageable means extending out beyond its side, a locking device comprising a hook having a bent upper portion, an arm pivotally mounted on the side of the car body and said hook being pivotally mounted near the upper end of said arm, the lower end of said hook engageable with the said means extending from the side of the door, a strap extending from the lower pivotal point of said arm to a point beyond the outer edge of the bent portion of said hook and a dog pivotally secured behind one end of said strap, a pivotal support for the outer end of said arm extending outwardly beyond the hook, and adapted to be engaged by a member to force the said hook upwardly to thereby raise the door and lock the same and to force the hook rearwardly to lower the door and unlock the same and said dog adapted to be swung into position to prevent accidental disengagement of the hook with the door.
25. 8. In combination with a car having a drop door, a locking device comprising an arm, a hollow sleeve formed at one end of the arm and an opening formed in the lower end thereof, a bearing post passed within said opening and riveted to the car body, a bent hook pivotally mounted on the sleeve formed on said arm, the upper end of said hook when in its uppermost position lying
- to one side of the axial point of said arm, a strap integrally secured with the end of said bearing post, said strap riveted to the side of the car body and a dog secured behind said strap and adapted to be thrown into and out of contact with said hook, means extending from the side of the car door adapted to be engaged by said hook and said sleeve presenting a surface for engagement so that said hook may be manually forced upwardly to thereby raise and lock the door and rearwardly to unlock and lower the door.
30. 9. In combination with a car having a drop bottom door, a member secured to the side of said door in the form of a bracket, a locking device comprising a hook, the jaw of which is adapted to engage with said bracket, an arm pivotally secured to the car body and above said bracket when the door is in its closed position, a pin formed on the outer end of said arm and the said hook pivotally mounted on said pin, means extending from the lower pivotal point of said arm rearwardly for retaining the hook on said pin, a dog also held to the car body by said means, said hook adapted to be raised to close the door and lock the same in its closed position and to be lowered to support the door in a partly raised position and the pin on said arm limiting the downward movement of said hook.
35. 10. A locking device for drop bottom doors comprising an arm, said arm provided with an outstanding lug at one end and a boss at the other end, a bearing post fitting within said boss and formed on a strap, a curved hook pivotally mounted on the outstanding lug, a dog secured to the rear end of said strap, the lug on the outer end of said arm being hollow to receive a bar for operating said locking device and said lug also limiting the downward movement of said hook, the upper end of said hook resting on the outer surface of the boss formed in the lower end of said arm when said hook is in its uppermost position.
40. 11. In combination with a freight car having a drop door, a member extending transversely and beyond the sides of said door and brackets secured near the opposite ends of said transverse member, said brackets being each provided with two side walls, hooks eccentrically mounted on the opposite sides of said car and each hook being adapted to pass respectively between the side walls of the brackets, said hooks when swung upwardly supporting and locking the door in its final position and said hooks in conjunction with said brackets, preventing lateral movement of said door.
45. 12. In a door mechanism for railway cars, a door hinged to the car body, the same having a bracket affixed thereto comprising a locking face, a locking member swing-

- 2
- ingly carried upon the car body and arranged for locking engagement with the locking face of the said bracket, the said locking member being so connected to the car body as to be capable of bodily movement with respect thereto independently of its swinging movement.
13. In a door arrangement for railway cars, a door hinged to the car body, a link pivoted to the car body near an edge of the door, and a door-engaging hook pivoted upon the link, the parts being so formed and associated that when the link is in one position the hook may be engaged or disengaged with the door, but when the link is in another position the hook and door will be interlocked to prevent disengagement.
14. In a door arrangement for railway cars, a door hinged to the car body, a link pivoted to the car body near an edge of the door, and a door-engaging hook pivoted upon the link, the parts being so formed and associated that when the link is in upright position the hook and door will be interlocked to prevent disengagement.
15. In a door arrangement for railway cars, a door hinged to the car body, an arm rotatably mounted upon the car body near an edge of the door, and a door-supporting hook pivoted upon the arm and arranged to be swung into or out of engagement with the door when the arm is in one position, the arm being arranged to exert a lifting motion to the hook and the hook-engaged door upon rotation of the arm, the engagement of the hook with the door being of such a character that disengagement of the hook from the door is impossible while the said parts are in such lifted positions.
16. In a door device for railway cars, a door hinged to the car body, a door-supporting hook pivoted to the car body adjacent an edge of the door, an arm extending outwardly from the door, the same having a hook seat formed thereupon, and stop walls formed on the arm at either side of the said hook seat.
17. In a door device for railway cars, a door hinged to the car body, a door-supporting hook pivoted to the car body adjacent an edge of the door, an arm extending outwardly from the door, the same being formed of a member of angular section, a hook seat member secured to the arm, the same being arranged within the interior angle of the arm section and being provided with an end wall extending interiorly across the angle of the arm section and adapted to tie the legs thereof together and to arrest creepage of the hook along the arm.
18. In a door device for railway cars, a door hinged to the car body, a door-supporting hook pivoted to the car body adjacent an edge of the door, an angular member secured to the door and extending outwardly therefrom to form a hook-engaging arm, and an adapter casting attached to the angular member, and arranged to stiffen the same and to form a hook seat, said adapter casting being arranged to fit the contour of the interior angle of the angular member and being secured thereagainst.
19. In a door device for railway cars, a door hinged to the car body, a door-supporting hook pivoted to the car body adjacent an edge of the door, a member of angular section secured to the door and extending outwardly therefrom to form a hook-engaging arm, the hook being arranged to engage the arm below one leg of the said angular member, and an adapter member secured to the arm, the same being formed to fit the contour of the angular member and to form a hook seat therebeneath.

In testimony whereof I affix my signature.
WILLIAM E. WINE.
